DESIGN FOR A COAT

Maurice Hirsh, New York, N. Y.

Application July 7, 1936, Serial No. 63,691

Term of patent 3½ years

To all whom it may concern:

Be it known that I, Maurice Hirsh, a citizen of the United States of America, residing in Manhattan, county of New York, and State of New York, have invented a new, original, and ornamental Design for a Coat, of which the following is a specification, reference being had to the accompanying drawing, forming part thereof, wherein,

The characteristic feature of my design resides in the strap-like member on the sleeves, shoulder and collar of the coat, as shown.

I claim:

The ornamental design for a coat, substantially as shown and described.

MAURICE HIRSH.
